DIMMER AND TURN SIGNAL CONTROL
MECHANISMCleo C. Stratton, 1732 Mallory St.,
San Bernardino, Calif.
Filed Dec. 26, 1963, Ser. No. 333,555
5 Claims. (Cl. 200—61.29)

This invention relates generally to electric switches and relates more particularly to directional signals for automobiles and the like.

While the invention has particular utility embodied in directional signals for automobiles, and is shown and described as embodied therein, it is to be understood that its utility is not confined thereto.

One of the problems of present directional signals for automobiles and the like is that of the return of the switch to the off position after a signal has been given and the operator has completed the turn. This is a particular problem when changing lanes, since the wheels of the automobile are not turned a sufficient distance so that the directional signal switch will be opened when the automobile is straightened out after the change in lanes has been completed.

It is therefore an object of the invention to provide a directional switch that will minimize or overcome this difficulty.

It is another object of the invention to provide a switch mechanism of this character that is foot operated.

It is still another object of the invention to provide a switch mechanism of this character that is combined with the dimmer switch.

It is a further object of the invention to provide a switch mechanism that is relatively simple in construction.

It is a still further object of the invention to provide a switch mechanism of this character wherein patentable novelty resides in the directional switch means per se.

It is another object of the invention to provide switch means of this character that is relatively inexpensive to manufacture.

It is still another object of the invention to provide switch means of this character that may be easily and quickly installed.

The characteristics and advantages of the invention are further sufficiently referred to in connection with the following detailed description of the accompanying drawing, which represents one embodiment. After considering this example, skilled persons will understand that variations may be made without departing from the principles disclosed and I contemplate the employment of any structures, arrangements or modes of operation that are properly within the scope of the appended claims.

Referring to the drawings, which are for illustrative purposes only:

FIG. 1 is a side elevational view of a switch mechanism embodying the present invention;

FIG. 2 is an end view with the adjacent directional switch removed;

FIG. 3 is a sectional view taken on line 3—3 of FIG. 1;

FIG. 4 is an enlarged longitudinal sectional view taken on line 4—4 of FIG. 1; and

FIG. 5 is an enlarged top plan view.

Referring more particularly to the drawings, there is shown diagrammatically or schematically a switch mechanism embodying the present invention.

Referring to FIGS. 1, 2 and 3, there is shown a portion of a floor board 10 of an automobile, said floor board having an opening 11 therethrough for reception of the switch box 12 of a dimmer switch, indicated generally at 14, said switch box having a top plate 15 secured to the top side of said floor board 10 by screws 16. The dimmer switch is of any well known type and

2

includes a barrel 17 extending upwardly of the switch box and secured to the plate 15 thereof. The switch mechanism is disposed within the switch box 12 and is actuated by a plunger 17a, disposed within the barrel 17 and carrying a cap 18 at the upper end which slidably fits on the upper end portion of the barrel 17. There is sufficient clearance between the upper end wall 19 of the cap and the adjacent upper end of the barrel to permit sufficient downward movement of the cap to actuate the switch mechanism disposed in the switch box 12. There is a spring 17b within the barrel 17 which urges the cap 18 upwardly to its upper limit of movement so that said cap is normally at its raised or uppermost position.

15 There is a beam 20 having depending flanges 21 secured thereto intermediate the ends thereof and straddling the cap 18, said flanges 21 being pivotally mounted on screws 22 which extend through openings provided therefor in said flanges and screwed into tapped openings provided therefor in the cap 18 at diametrically opposite sides thereof. Thus the beam 20 is adapted to see-saw on the screws 22. In order to maintain the beam 20 in a position substantially normal to the axis of the barrel 17 there is a spring 23 disposed between the top or end wall 19 of the cap 18 and the underside of the beam 20, the central portion of beam 20 being spaced upwardly of the upper end of the cap 18 of the dimmer switch to provide space for said spring 23 and operating space for the see-saw movement of said beam, as will be described more particularly hereinafter.

20 The beam 20 is provided with foot pads 24 and 25 at the respective ends thereof and a central foot pad 26. Pads 24, 25 and 26 are of rubber or any other suitable material and may be attached in any suitable manner. 25 For example, each pad may have an opening in one side for slidably reception of the end portion of the beam 20. They may alternatively be secured to the beam by any suitable adhesive. The central pad 26 is secured to the top side of the beam by any well known adhesive or by any other suitable means.

30 There is a directional switch at each side of the barrel 17, said directional switches being indicated generally by the respective reference characters S-L and S-R. These switches are of the same construction and operation and are secured to the beam 20, as will be described more particularly hereinafter. Since these switches S-L and S-R are of the same construction and operation, a description of one will suffice.

35 Referring to FIG. 4, there is shown a longitudinal sectional view of one of the directional switches. The switch comprises a body 30 of electrically insulating material, said body having an axial bore 31 therethrough. At one end there is an annular flange or extension 32 defining an enlarged chamber 33 and at the opposite end there is a reduced diameter end portion 34. The material of the body is of a relatively stiff plastic or the like, such as Bakelite, for example. There are, of course, various other well known materials of suitable character.

40 A plug 35 is secured in the upper end of the chamber 33 by any suitable means, such as, for example, a screw 36, which is disposed in an opening provided therefor in the flange 32 and screwed into a tapped bore 37 in said plug. At its inner end the plug 35 is provided with a reduced diameter spring retaining portion 38 having an electrical contact 39 arranged axially thereof and embedded or otherwise suitably secured in said plug. A diagonally arranged passage or bore 40 is provided in the plug for reception of an electrical wire 41 having its inner end soldered or otherwise suitably secured to said contact 39. Plug 35 is also provided with an axial tapped bore 42 extending inwardly from the outer end thereof for reception of a screw 43 whereby the switch

is attached to the beam 20. The screw 43 extends through an opening provided therefor in said beam and extends part way through said plug, so that its inner end is spaced from the contact 39.

A tubular bearing or sleeve 45 is disposed within the bore 31 of the switch body, said bearing being secured in said bore by any suitable means such as press fitting, for example. Slidable within the sleeve or bearing 45 is a rod 46 having a head 47 of greater diameter than said rod, said head having an upturned annular flange 48 thereon for reception of the lower end of a spring 49. The upper end of spring 49 is disposed about the spring retaining part 38 of the plug 35 and said spring urges the head, and hence the plunger 46, downwardly. Engagement of the head with the upper end of the sleeve or bearing 45 limits downward movement of said plunger, the lower end of said plunger extending downwardly or outwardly of the bearings or sleeve 45 and body 30 of the switch. The head 47 of the plunger 46 is provided with a contact point 50 in alignment with the contact 39, so that when the plunger 46 moves upwardly or inwardly the contact 50 will engage the contact 39, thereby closing the switch. An electrical wire 51 is disposed in a passage or opening in the body 30 and is soldered or otherwise secured to the sleeve 45. Thus when the contact points 50 and 39 are in engagement there is completed a connection through the switch.

At the lower end of the body 30 there is disposed a flexible cap 53 of insulating material, such as rubber or the like. The open upper end of the cap 53 receives the reduced diameter portion 34 of the body 30 and said cap may be secured to the body by a suitable adhesive or the like.

The depending or outwardly extending lower end portion of the plunger extends into engagement with the lowermost portion of the cap 53 and it is to be understood that the plunger has a loose enough fit in the sleeve or bearing 45 so that air in the chamber formed by the cap 53 may pass upwardly and downwardly with corresponding movements of the lower end of cap 53. Chamber 33 at the upper end of the switch is vented to atmosphere by means of a vent 54.

There are a pair of leaf springs 57 and 58 at each side of the barrel 17 of the dimmer switch. Each of these springs have its inner end secured to the plate 15 by any suitable means such as spot welding or the like and is inclined upwardly and outwardly relative to said barrel so that they are operably disposed beneath the respective directional switches S-L and S-R. Normally the resilient end portions of said springs 57 and 58 are spaced beneath the lower ends of the respective directional switches and are also spaced upwardly of the plate 15 so that they may flex downwardly when engaged by the lower ends of said dimmer switches when the beam 20 is actuated in one direction or the other.

Assuming it is desired to indicate a left hand turn, the beam 20 is actuated in the counterclockwise direction by pressure of the operator's foot on the pad 24. As the beam 20 is moved in the counterclockwise direction the lower end of the switch S-L engages the outer resilient end portion of the leaf spring 57. This spring is sufficiently stronger than the spring 49 of the switch and the resilience of the rubber cap 53, so that said spring 49 and cap 53 will yield and cause the plunger 46 to move upwardly to effect electrical engagement between the contact 50 and the contact 39, thereby closing the switch. Additional pressure will, of course, cause the spring 57 to yield. When pressure is released on the pad 24 the beam 20 will return to its normal horizontal position. Pressure on the pad 25 will effect movement of the beam 20 in the clockwise direction and close the switch S-R in the manner just described in connection with the switch S-L.

When it is desired to dim the lights, foot pressure is applied to the pad 26 to effect downward movement of

the cap 18 to thereby actuate the dimmer switch. The portions of the leaf springs 57 and 58 disposed between the respective directional switches S-L and S-R are spaced downwardly from the lower ends of said directional switches a sufficient distance so that when pressure is applied to the pad 26 the cap 18 of the dimmer switch may move the full distance required to effect operation of said dimmer switch for dimming the lights before the lower ends of said directional switches engage said springs 57 and 58.

It is to be understood, of course, that the dimmer switch circuit is the same as that presently in use and the directional switches S-L and S-R are arranged in suitable circuits for controlling the respective lights for indicating left-hand and right-hand turns.

The invention and its attendant advantages will be understood from the foregoing description and it will be apparent that various changes may be made in the form, construction and arrangement of the parts of the invention without departing from the spirit and scope thereof or sacrificing its material advantages, the arrangement hereinbefore described being merely by way of example, and I do not wish to be restricted to the specific form shown or uses mentioned except as defined in the accompanying claims, wherein various portions have been separated for clarity of reading and not for emphasis.

I claim:

1. A switch mechanism, comprising:
  - (A) a dimmer switch having a switch box with switch mechanism therein, a plate at the top of said box whereby the dimmer switch may be attached to a support, a barrel extending upwardly of said plate and having a movable cap slidably disposed at the outer upper end thereof biased to an outer position and adapted to effect closing of said switch when moved downwardly, and effect opening of said switch when at said outer position;
  - (B) a beam centrally pivoted to said cap and spaced therefrom a sufficient distance to permit operable see-saw movement of said beam;
  - (C) yielding means normally positioning said beam in a neutral substantially horizontal position;
  - (D) a foot pad attached to each end of said beam and a foot pad attached to the central portion thereof;
  - (E) a directional switch at each side of said barrel;
  - (F) each of said switches comprising a body of insulating material having an annular upwardly extending cylindrical flange defining a chamber, said body having an axial bore therethrough and a reduced diameter lower end portion;
  - (G) a plug secured in the upper end of said chamber;
  - (H) means securing said plug to the adjacent portion of said beam;
  - (I) an electrical contact secured to the inner end of said plug;
  - (J) a tubular bushing secured in said bore;
  - (K) a plunger slidably disposed in said bushing and having a head at the upper end;
  - (L) a movable contact secured to the upper end of said head and movable into and out of engagement with said fixed contact with corresponding movements of said plunger;
  - (M) yielding means urging said head and plunger downwardly into engagement with the upper end of said bushing;
  - (N) a hollow resilient cap attached to the reduced diameter lower end portion of the switch body, the lower end of said plunger engaging the lower central portion of said cap;
  - (O) wires for the respective contacts for connecting same into respective electrical circuits;
  - (P) and yielding means for each directional switch, each yielding means having one end attached to the plate of the switch box and having the other end disposed beneath the respective directional switch,

said one end of said yielding means being spaced from the adjacent end of said respective directional switch.

2. A switch mechanism, comprising the combination of:

- (A) a dimmer switch having a switch box with switch mechanism therein, a plate at the top of said box whereby the dimmer switch may be attached to a support, a barrel extending upwardly of said plate and having a movable cap slidably disposed at the outer upper end thereof biased to an outer position and adapted to effect closing of said switch when moved downwardly a predetermined distance and effect opening of said switch when moved to said outer position;
- (B) a beam centrally pivoted to said cap and spaced therefrom a sufficient distance to permit operable see-saw movement of said beam;
- (C) yielding means normally positioning said beam in a neutral substantially horizontal position;
- (D) a foot pad attached to each end of said beam and a foot pad attached to the central portion thereof;
- (E) a directional switch at each side of said barrel, the upper end of said switches being secured to the beam;
- (F) each of said switches comprising a body of insulating material having an annular upwardly extending cylindrical flange defining a chamber, said body having an axial bore therethrough, a plug secured in the upper end of said chamber;
- (G) an electrical contact secured to the inner end of said plug;
- (H) a movable plunger operably disposed in said bore and having a head at the upper end;
- (I) a movable contact secured to the upper end of said head and movable into and out of engagement with said fixed contact with corresponding movements of said plunger;
- (J) yielding means urging said head and plunger downwardly;
- (K) a resilient wall defining a hollow resilient cap attached to the lower end portion of the switch body, the lower end of said plunger engaging the resilient wall of said cap;
- (L) and yielding means for each directional signal, each yielding means being attached to the plate of the switch box and having a resilient yielding portion disposed beneath a respective directional switch, said yielding portion being spaced from the adjacent end of said respective directional switch.

3. A switch mechanism, comprising:

- (A) a dimmer switch including a switch box, a plate at the top thereof, a barrel extending upwardly of said plate and having a movable cap slidably disposed at the outer upper end thereof for actuating said dimmer switch;
- (B) a beam;
- (C) pivot means adjacent the longitudinal center of said beam connecting said beam to said cap for operable see-saw movement of said beam on said cap;
- (D) yielding means engaging said beam and normally positioning said beam in a neutral substantially horizontal position;
- (E) a normally open directional switch at each side of the pivotal connection of said beam, said switches being secured to the beam and movable therewith and each switch having a movable member for closing same when said movable member is actuated in one direction;

(F) yielding means biasing each movable member for actuating same in the opposite direction for opening said switch;

(G) and yielding means for each directional switch, said yielding means being positioned relative to its respective directional switch for exerting pressure on the movable member thereof to effect movement of said movable member in the switch closing direction after said directional switch has been moved a predetermined amount toward said yielding means.

4. In a switch mechanism:

- (A) a dimmer switch having a movable switch actuating member;
- (B) a beam pivoted to said switch actuating member adjacent the longitudinal center of said beam and having see-saw movement thereon and engageable at either end for operation;
- (C) yielding means normally positioning said beam in a neutral position;
- (D) a normally open directional switch secured to the beam at each side of its pivot;
- (E) and yielding means for closing respective switches upon pivotal movement of said beam in respective directions, said yielding means being in the path of movement of the directional switches, said dimmer switch being closed upon actuation of said beam by pressure in the region of its pivotal connection with said movable switch actuating member.

5. An electric switch, comprising:

- (A) a body of insulating material having an annular cylindrical flange at one end defining a chamber at said one end, said body having an axial bore therethrough and a reduced portion at the end opposite said flange;
- (B) a plug of insulating material secured in the upper end of said chamber;
- (C) a fixed electrical contact secured to the inner end of said plug;
- (D) a tubular bushing secured in said bore;
- (E) a plunger slidably disposed in said bushing and having an enlarged head at the end adjacent the fixed contact, said plunger having a normal position spaced from said fixed contact;
- (F) a movable contact secured to said enlarged head of said plunger, said movable contact being movable into and out of engagement with said fixed contact with movements of said plunger toward and away from said fixed contact;
- (G) yielding means urging said plunger to said normal position;
- (H) and a hollow resilient cap attached to the reduced diameter end portion of the switch body, the end of said plunger opposite the head thereof engaging the lower central portion of said cap.
